UNITED STATES PATENT OFFICE

2,524,578

STITCH REGULATING MECHANISM

Eugene St. Pierre, Pawtucket, and Joseph Wawzonek, Central Falls, R. I., assignors to Hemp-hill Company, Central Falls, R. I., a corporation of Massachusetts

Application November 22, 1947, Serial No. 787,520

2 Claims. (Cl. 66—54)

1

This invention relates to a new and useful improvement in mechanisms for obtaining the different lengths of stitches required for the several parts of a stocking and to a mechanism for fashioning the leg. As hereinafter shown and described, the invention is applied to a circular, independent needle, knitting machine of the Banner type. It can also be used on other machines of the same general character and those in which the cams rotate about the needle cylinder. Nor is it limited to hosiery machines.

The making of various parts of a stocking such as the top, leg, high splice, heel, sole, toe, etc., generally require several different yarns used at different times. These changes of yarns and other considerations involve changes in the length of the stitches or loops. That is to say, in the top the loops are of one length, in the leg they are of another and so on throughout the stocking. These periodic changes of loop length for the various parts are obtained by raising or lowering the cam block or blocks upon which the knitting cams are mounted so that the height of the needle hooks in relation to the drawing surface of the sinkers may be varied.

In addition to the periodic alterations of loop length characteristic of the different parts of the stocking, it is sometimes desirable to vary the loop length within one or more of these parts, particularly the leg, to shape or fashion it to a suitable outline. A device for carrying out these objects in relation to the main cam block forms the subject matter of Patent No. 2,135,185.

A device in which these objects are gained in relation to both main and auxiliary cam blocks is disclosed and claimed in Patent No. 2,369,780. The object of the present invention is to carry forward and perfect more highly the device of the general type of the latter patent so that stitch length adjustments and fashioning at either the main or auxiliary cam block can be accomplished more accurately and easily. There is further provided by this invention means whereby the adjustment of both cam blocks is effected simultaneously by a master controlling means without disturbing the normal arrangement of stitch length adjusting means individual to the respective cam blocks.

The form of the invention selected for description herein is shown in the drawings of which:

Fig. 1 is a front elevation of that part of a stitch regulating mechanism which will hereinafter be referred to as a fashion bracket;

Fig. 2 is a side elevation of essentially the same part;

2

Fig. 3 is a top plan view of the fashion bracket and its operating connections to the cam block supports; and

Figs. 4 and 5 are details of parts of the fashion bracket shown in the previous figures to illustrate the manner in which it operates and Fig. 6 is a detail of other parts.

As already stated, the device shown in the drawing is of a type suitable for application to a hosiery knitting machine of the Banner type. Also, as already stated, its objectives are to a considerable degree similar to those of the device of Patent #2,369,780 and its general position upon the machine may be similar to that of the device of that patent.

As shown in Fig. 3, the machine is provided with the usual cam plates 1 and 2 upon which the main and auxiliary cam blocks, respectively are mounted. Plate 2 in the form shown may also support a second auxiliary cam block if the machine is arranged for two feed knitting at the auxiliary side.

Cam plate 1 is attached to a vertically slidable rod 3, the lower end of which rests upon a mid-point 4 on the lever 5 pivoted at 6 and extending to a point 7 above the adjustable screw 8 which is threaded into a lug 9 of a block 10 by which it is supported.

Cam block plate 2 (Fig. 3) slides upon a guide 11 and its lower end bears upon and is supported at a mid-point 12 of a lever 13 which is pivoted at 14 and extends to a point 15 overlying an adjustable screw 16 (Fig. 1) by which it is supported. Screw 16 is threaded into an arm 17 attached to a block 18.

Blocks 10 and 18 are independently slideable upon a slide 19 supported upon a suitable part of the machine by a bracket 20. Therefore, it will be evident that by causing blocks 10 and 18 to move up or down plates 1 and 2, respectively, will be similarly moved to alter the heights of the main and auxiliary cam blocks, respectively, in relation to the sinkers.

By operatively connecting the cam plates 1 and 2 to mid-points 4 and 12 of levers 5 and 13, respectively, the distance through which each plate and its associated cam block is moved is much less than the movement of the controlling blocks 10 or 18. Therefore, the movements of the blocks can be conveniently large, relatively speaking, and minor inaccuracies in the operating parts such as are necessarily permitted in commercial manufacture or in the adjustment of such parts will be reflecting the movements of the cam blocks only to a negligible degree.

The mid-points referred to are not necessarily midway between the ends of levers 5 and 13. They may be at any desired points between these ends such as the positions shown in Fig. 3. Preferably, these points 4 and 12 are equidistant from the lever pivots 6 and 14, respectively, and also equidistant from screws 8 and 16, respectively, so that equal and similar movements of levers 5 and 13 will produce equal and similar movements of the cam block plates 1 and 2 although of less magnitude.

Block 10 has a projection 21 through which are threaded a set 22 of screws. Block 18 has a similar projection 23 through which are threaded a set 24 of screws. Upon block 18 are mounted a series of slides shown in Fig. 1 as twelve in number held equally spaced apart by suitable guides so as to be vertically movable. The spacing of the slides is such that each is in alignment with a different one of the screws of each set 22 and 24 on blocks 10 and 18, respectively. Each of these slides is urged upward by a plunger 26 backed by a spring 27 mounted in a recess 28 of block 18 so that each is resiliently held against a corresponding screw of sets 22 or 24 depending upon the settings of these screws. Therefore, there is a continuous chain of mechanical connections between the cam blocks and the slides.

Beneath the lower ends of all but one slide, eleven in Fig. 1, is a drum 29 provided with cams such as 30 all of which are of the same height spaced around and across it and so arranged that at all times there will be a cam under one of the slides associated with the main cam block and so that there will be a cam under one of the slides associated with the auxiliary cam block at all times except one, as will be explained later.

The slide associated with a cam block will change whenever that block is to be repositioned and for each change required a cam must be positioned beneath the changed slide. The cams supply a laterally shifting base of fixed elevation so that the heights of the respective cam blocks are determined by screws 22 and 24.

As shown in Fig. 1, there is a fashioning disc 31 alongside drum 29 which is adapted to engage with the 12th or right slide 32 of the group. Drum 29 is turned intermittently by the well known pattern drum operating mechanism controlled from the pattern chain of the machine. The fashioning disc 31 is operated at times by its own pawl 33 through ratchet 34 (Fig. 1) and at other times by pattern drum 29. The general arrangement of the pattern drum and fashioning disc and their operating mechanism are similar to those shown in Patent No. 2,369,780 and are too well known to require further description here.

The slide 32 operates with both main and auxiliary cam blocks to establish their height. Therefore, while the fashion disc 31 is in action, no cams 30 are beneath their respective slides or, if beneath, are not operative.

For the stitch length adjustments of the major parts of the stocking two slides such as those shown in Figs. 4 and 5 may be used. These are numbered 35 and 36 to identify them from the others. Slide 35, as already explained, is urged upwardly by plunger 26 and spring 27 against the corresponding screw 37 of set 22 in projection 21 of block 10. Similarly, slide 36 is in contact with screw 38. Screws 39 and 40 are backed off sufficiently to be inoperative. Therefore, when drum 29 is turned to bring two of the cams 30 under slides 35 and 36, the main cam block will

be positioned at the height determined by the adjustment of screw 37 and the auxiliary cam block will be positioned at the height determined by screw 38. When a cam 30 passes from under slide 35 or 36, this slide although it still maintains contact with screw 37 or 38 no longer functions as a part of the supporting means for its cam block. This function has been assumed by others of the slides under which cams have become positioned and the heights of the cam blocks have been determined by screws corresponding to these substituted slides.

A single slide, such as 35, can also be used to determine the adjustments or positions of both main and auxiliary cam blocks simply by adjusting screws 37 and 39 as desired and so that they both will contact slide 35 when it is upon a cam 30. However, any change of this sort will destroy its previous adjustment.

There are times when it is desirable that the height of both cam blocks be controlled from a single source so that they can be moved in unison and to the same degree without disturbing their relative adjustments. For example, in three feed knitting at both the main and auxiliary cam blocks, particularly of sheer fabric in which equality of loop length is of vital importance, it is essential that all of the knitting cams shall have exactly the same heights in relation to the sinkers and shall maintain these same relative heights even though the actual heights are varied periodically throughout the knitting of certain parts of a stocking. To this end, master controls are included in this invention whereby both cam block supports can be adjusted, as above described, through the operation of a single support. At least some of the slides shown in Figs. 4 and 5 will not be available for this purpose, if the individual adjustments of the two cam blocks are to be preserved.

A suitable form is shown in Fig. 6. This consists of a slide 32 having an end 41 cooperating with one of the cams 30 in the manner previously described with respect to slides 35 and 36. Above this is a second slide 42 having an offset end 43 through which a screw 44 is threaded so as to be engageable with slide 32. Support 42 also has a projection 45 underlying screw 46 of set 24 in block 18 and the upper end 47 of slide 42 underlies screw 48 of set 22 in block 10. Since blocks 10 and 18 are operatively connected to the main and auxiliary cam blocks, it will be evident that when a cam 30 underlies a slide 32 the device described will determine the actual positions of both cam blocks through the screw 44 without altering their relative positions.

The height of each cam block can be set manually at any time through screws 46 and 48 to correct any deviation from the desired relative condition and a common change in the setting of both blocks can be made at any time by means of screw 44 without disturbing the relative settings of the individual blocks.

For example, in multi-feed knitting, it is essential that all of the loops knitted at all of the blocks be of the same length. The setting of the main and auxiliary blocks can be obtained by adjusting the screws 46 and 48 which control the heights of the individual blocks. If it happens that the loops knit at all blocks are of equal length but too long or too short, this can be remedied by means of screw 44 without disturbing the adjustments just mentioned. In Fig. 1, five of these devices are shown interspersed among the individual slides previously described.

The number and arrangement of all of these controls can be varied as desired.

The type of device shown in Fig. 6 is well adapted to control both cam blocks simultaneously during the shaping of the leg by means of the fashioning disc 31. As shown in Fig. 2, while the fashioning disc 31 is in action, there are no cams 30 under any of the other slides so that the fashioning disc controls all of the cam blocks. For all practical purposes, it is simply another cam 30 having a progressively increasing height instead of a single height.

We claim:

1. In a circular, independent needle, knitting machine having vertically movable main and auxiliary knitting cam supports, stitch regulating mechanism which includes means associated with each cam block support for determining its operating height, a support beneath said means and held resiliently in contact therewith and means positionable beneath said last mentioned support for fixing its position.

2. For a circular, independent needle, knitting machine having vertically movable main and

auxiliary cam plates, a stitch regulating mechanism which includes a vertically movable slide, means operatively associated therewith for establishing the height of each cam plate independently of the other in relation to said slide, a second vertically movable slide below and in alignment with said first mentioned slide, means associated with said slides for establishing a definite vertical spacing between them and means for causing said second slide to become fixed periodically.
